UNITED STATES PATENT OFFICE.

YOSHEP LUBAS, OF CHICAGO, ILLINOIS.

ADJUSTABLE BED-TABLE.

1,280,257.

Specification of Letters Patent.

Patented Oct. 1, 1918.

Application filed November 21, 1917. Serial No. 203,186.

To all whom it may concern:

Be it known that I, YOSHEP LUBAS, a citizen of the United States, residing at Chicago, in the county of Cook and State of Illinois, have invented certain new and useful Improvements in Adjustable Bed-Tables; and I do hereby declare the following to be a full, clear, and exact description of the invention, such as will enable others skilled in the art to which it appertains to make and use the same.

This invention relates to improvements in table attachments for beds.

The object of this invention is to provide a table capable of being secured to any type of bed whereby it may be moved into various adjusted positions with relation to the bed by the occupant of the bed or other persons.

A still further object of this invention is to provide a device of this character, which will be simple, practical and comparatively inexpensive in construction, and one that can be manufactured and sold at a low cost.

With these and other objects in view, the invention consists in the novel combination and arrangement of parts as will be herein-after more fully described and set forth in the claims hereto appended.

In the drawing

30 Figure 1 is a side elevation of my improved table attachment as applied to a bed,

Fig. 2 is an end elevation of the same,

Fig. 3 is a fragmentary detail sectional view illustrating the parts connected together,

Fig. 4 is a detail sectional view,

Like numerals of reference designate corresponding parts in all the figures of the drawing.

40 Referring to the drawing, the numeral 5 designates a bed of the type in general use and comprises a head board 6, a foot board 7, and connected together by the side rails 8, and end rails 9. The foot board and head board are each provided with spaced transversely extending brace bars 10.

My improved attachment comprises a standard 11 having a vertical member 12 and a horizontal member 13. The horizontal 50 member has its end terminating in a bearing eye 14 and the lower end of the vertical member has secured thereon a bevel gear 15, which gear is adapted to mesh with a bevel gear 16 carried by one end of the stub shaft 17, which stub shaft is rotatably supported in the bearings 18, which bearings have se-

cured thereto the hooks 19 which are adapted to be arranged over one of the braces 9 of the foot board of the bed to support the stub shaft thereto. The stub shaft is provided and has formed integrally therewith the collars 20 which are arranged on opposite sides of the bearings 18 to prevent longitudinal movement of the stub shaft with relation thereto. The vertical member 12 of 60 the standard is journaled in a bearing 21 removably supported on the foot board by the hooks 22 which are formed integrally with the bearing. A bracket 23 is substantially U-shaped and has its arms terminating into 65 bearings 24, one of which bearings is rotatably supported about the vertical member 12 of the standard, and this standard is held against vertical movement by the stop collar 25 which abuts one of the bearings 24. The 70 opposite bearing is journaled to one end of the stub shaft 17 as illustrated in Fig. 2 of the drawing.

The free end of the stub shaft has formed integrally thereon a bevel gear 26 which is 80 adapted to mesh with a bevel gear 27 formed on one end of the shaft 28, which shaft is removably supported upon one side rail of the bed by the hooks 29, which hooks have formed integrally therewith the bearings 30, which rotatably support the shaft 28. The shaft 28 is held against longitudinal movement by the collars 31 formed integrally with this shaft and on opposite sides of the bearings 30. The 85 free end of the shaft 28 has formed integrally therewith a bevel gear 32 which is adapted to mesh with the bevel gear 33 formed integrally with the shaft 34, which shaft has formed integrally with its upper end a crank handle 35, which facilitates the rotation of the gear 33, shaft 28 and standard 11. The shaft 34 is journaled to the side rail bearings 36 carried by arm 37, which arm is formed integrally with the bearing 38 90 journaled upon the shaft 28. The bearing has formed integrally therewith and depending therefrom an angular arm 39 which has a bearing 40 thereon which has journaled therein the lower end of the shaft 34 to permit of its free rotation.

The vertical arm 41 has one end reduced as at 42 forming a shoulder 43, which reduced end is journaled in the opening 44 in the horizontal portion 13 of the standard 11 and the shoulder abuts the under side thereof. A wing bolt 44 is screw threadably

mounted upon the reduced end 42 and bears against the upper side of the member 13 and holds the arm 41 against rotational movement with relation to the member 13 of the 5 standard. The lower end of the arm 41 is bent laterally in a horizontal plane as at 45 and has secured thereon a table 46, thus it can be seen that the table may be arranged at any angled position with relation to the 10 member 13 through the medium of the wing bolt 44.

In operation, it is only necessary for the 15 crank handle 35 to be rotated in either direction, thus imparting rotation to the shaft 28 which in turn rotates the stub shaft 17, which in turn rotates the standard 11 and thereby moving the table in the arc of a circle and in various adjusted positions with 20 relation to the bed.

Having thus described my invention, what 25 is claimed is:

1. A device of the class described including a standard, a gear carried by the standard, a stub shaft having gears at opposite 30 ends, one of the gears meshing with the gear of the standard, a drive shaft, a gear at each end of the drive shaft and one of the gears meshing with the free gear of the stub shaft, a crank handle having a gear meshing with the gear on the free end of the drive shaft

whereby upon rotational movement of the crank, the drive shaft, stub shaft and standard will be rotated, and an arm rotatably supported by the standard and having a table secured thereto, as and for the purpose 35 specified.

2. In combination, a bed, a vertical standard journaled to the bed, a horizontal arm carried by the standard, a vertical arm rotatably and adjustably carried by the horizontal 40 arm, a table carried by the vertical arm, a gear carried by the standard, a stub shaft, a gear on each end of the stub shaft and one of the gears meshing with the gear of the standard, a drive shaft, gears at each end of the 45 drive shaft and one of the gears meshing with the gear on the free end of the stub shaft, a crank, a gear carried by the crank meshing with the gear on the free end of the drive shaft for causing the rotation of the 50 drive shaft, stub shaft and standard, and means for removably supporting the stub shaft and drive shaft to a bed, as and for the purpose specified.

In testimony whereof I affix my signature 55 in presence of two witnesses.

YOSHEP LUBAS.
